CLAIM

The ornamental design for a specialized NFC tag, as shown and described.

DESCRIPTION

FIG. 1 is a front perspective view of a specialized NFC tag showing our new design;

FIG. 2 is a front view of a specialized NFC tag;

FIG. 3 is a rear view of a specialized NFC tag;

FIG. 4 is a top side view of a specialized NFC tag.

FIG. 5 is a bottom side view of a specialized NFC tag;

FIG. 6 is a left side view of a specialized NFC tag; and,

FIG. 7 is a right side view of a specialized NFC tag.

The broken lines in the drawings showing elements of the specialized NFC tag represent unclaimed portions of the specialized NFC tag and form no part of the claimed design.
